WINDOW LOCK

John Ventura, Brooklyn, N. Y.

Application August 21, 1945, Serial No. 611,737

1 Claim. (Cl. 292—206)

1

This invention relates to window locks, and aims to provide a simple, inexpensive, and easily applied and operated safety window lock whereby when the window is closed the sashes will be securely held and locked in their closed positions. This therefore not only serves the purpose of a safety window lock against unauthorized opening of the window, but also provides a tight closure to more effectively keep out the cold in the winter and the heat in the summer.

The above and other objects will become apparent in the following description, wherein characters of reference refer to like-numbered parts in the accompanying drawings. Referring to the drawings, it is to be noted that they are intended for the purpose of illustration only, and that it is neither intended nor desired to limit the invention necessarily to the specific details of construction shown excepting insofar as they may be deemed essential to the invention.

Referring briefly to the drawings,

Fig. 1 is a fragmentary perspective view of a window illustrating the application of the safety lock thereto.

Fig. 2 is a cross-sectional view taken on the line 2—2 of Fig. 1.

Fig. 3 is a view similar to Fig. 2, showing a modified form of the device.

Fig. 4 is a plan view of Fig. 3.

Referring in detail to the drawings, the numerals 10 and 11 indicated the upper and lower window sashes, respectively. The bottom frame member of the sash 10 is shown at 12, and the top frame member of the sash 11 at 13.

An elongated flat plate or dog 14 has a circular opening 15 through one end thereof whereby it is pivotally secured through the medium of a screw 16 to the frame member 12 of the upper sash, and it is of sufficient length to extend nearly to the edge of the lower sash frame member 13, as shown. Intermediate the length of the dog 14, an upright pin or post 17 extends rigidly therefrom, and is provided with a groove or cut-out 18 on that side thereof facing toward the screw opening 15. At the free extremity of the dog 14, a second opening 19 may be provided therethrough for the purpose presently to be defined.

In association with the dog 14, an L-shaped member 20 having arms 21 and 22, is used. The arm 21 has an opening 23 therethrough of substantially the same diameter as the post 17, and is adapted to be positioned by slipping the opening 23 over the post 17 and then drawing it backward so that the forward wall of its opening 23 will register within the groove 18. A threaded opening 24 is provided through the arm 22 for a set screw 25 having an enlarged base 26 adapted to contact the side of the frame member 13. It is apparent that, upon tightening of the set

1 screw, the dog 14 will be held firmly against both frame members 12 and 13 to keep them at the same level and to prevent opening of the window. When the window is open, or when the lock is not in use, the member 20 is of course removed, and the dog 14 is swung into the position shown in Fig. 4 in broken lines.

Should the member 20 be unavailable in an emergency, the window can be less securely locked by merely driving a nail 27 through the opening 19 into the frame member 13.

Obviously, modifications in form and structure may be made without departing from the spirit and scope of the invention.

15 I claim:

In combination with the lower frame member of the upper window sash of a window and the upper frame member of the lower sash of the same, a releasable locking means comprising a dog pivotally secured at one end to the upper surface of said lower frame member and of sufficient length to extend part way across the upper surface of said upper frame member, said dog having a post extending rigidly upward therefrom intermediate its length, an L-shaped member comprising a pair of arms at substantially right angles to each other, one of said arms having a threaded opening therein and having a set screw in said threaded opening, the other of said arms having an opening through its end registerable over said post, said first arm extending downward from said second arm, said set screw being screwed against the vertical wall of said upper frame member to tighten said second arm against said post thereby releasably locking said dog against the upper surfaces of said frame members, said post having a groove cut out of that face thereof facing said upper sash intermediate the height of the post thereby providing said groove with a rear wall, a ceiling and a floor, that portion of the wall surrounding said opening through said second arm being registerable in said groove against said rear wall, said ceiling and floor preventing vertical up or down movement of said second arm.

JOHN VENTURA.
